UNITED STATES PATENT OFFICE.

WILLIAM ALFRED GAY, OF NEWARK, NEW JERSEY.

MUSICAL TOY.

1,089,699.

Specification of Letters Patent. Patented Mar. 10, 1914.

Application filed March 24, 1913. Serial No. 756,377.

To all whom it may concern:

Be it known that I, WILLIAM ALFRED GAY, a citizen of the United States, residing at Newark, in the county of Essex and State 5 of New Jersey, have invented a new and useful Improvement in Musical Toys, of which the following is a full, clear, and exact description, reference being had to the accompanying drawings, forming part of 10 this specification, in which—

Figure 1 is a longitudinal vertical section; Fig. 2 is a horizontal longitudinal section; Fig. 3 is a transverse vertical section showing one form of my invention; Fig. 4 15 is a plan view showing a modification; Fig. 5 is a longitudinal section showing another modification; and Fig. 6 is a section on the line VI—VI of Fig. 5.

My invention relates to an improvement 20 in musical toys of that class in which a number of rods or wires representing a musical scale or parts of the same are vibrated by suitable striking fingers or clappers.

The object of my invention is to provide a 25 toy of this character, which will not only be attractive and pleasing, but which can be constructed at a very small cost.

My invention may have any one of a number of different forms, some of which I have 30 illustrated in the accompanying drawings and which will now be described, it being premised, however that it is susceptible of various other modifications within the scope of the appended claims.

In that form of my invention shown in 35 Figs. 1, 2 and 3, the numeral 2 designates a casing shown as being of similar form to a piano casing. 3 designates a number of wires or rods supported in the lower portion of the case by driving them into a base 4, from which they project. The rods are otherwise unsupported and are free to vibrate. 5 designates a rotary shaft which may be actuated by a hand crank 6 and 40 which carries a number of radial projections 7, which, as the shaft is rotated are adapted to successively contact with a vibrator 8. This vibrator is pivoted at 9 and has suspended therefrom two striking fingers or 45 clappers 10. 11 is a leaf spring which is secured to the vibrator 8, and which projects for contact with a suitable stop 12, secured in the casing. The fingers or clappers 10 are flexibly suspended from the vibrator so 55 as to be capable not only of an up and down movement, but also of a lateral swinging

movement, as indicated in Fig. 3. In this manner, they are made to sweep over a number of the wires or rods in succession, giving forth a succession of musical notes. The 60 base in which the rods or wires are secured is preferably of hard wood, so as to be of a high degree of resonance. The case is also preferably constructed of wood and acts as a sounding box. By a proper adjustment of 65 the fingers or clappers, each double stroke will vibrate the same number of wires so that the harmonies of a musical scale are sounded as the device is operated.

In Fig. 4 I have shown the application of 70 my invention to a wheeled toy. This form consists of a box or casing 13, mounted upon the four wheels 14. 15 designates the series of wires or rods which are secured in one end of the casing. 16 is a vibrator which is 75 pivoted on the vertical axis 17 to oscillate in a horizontal plane. A striking finger or clapper is suspended at 18 from each corner of the free end portion of the vibrator. These fingers or clappers are similar to those 80 first described. The vibrator is actuated by a pitman 19, connected to the vibrator at the corner portion thereof, opposite the pivot 17, and also connected to a crank 20 in one of 85 the wheel axles 21.

In Figs. 5 and 6, I have shown another embodiment of my invention, in which the rods or wires 22 are arranged in circular form within a cylindrical drum-like casing 23, which can be rolled along the floor or 90 other surface. 24 is a wire placed loosely around an internal shaft 25 of the drum and having a striking finger or clapper 26, suspended from each end portion thereof. As the drum is rolled, the striking fingers will 95 successively contact with two separate wires at each double stroke. The casing 24 is preferably constructed of hard wood, as in the other forms, so as to increase the resonance effect. By arranging the striking fingers at 100 the right distance from each other with the wires of the musical scale so spaced and adjusted that they can successively contact with all of the wires, two at a time, harmonies will be produced which will be 105 snatches of simple musical melodies, sometimes two entire bars of a popular tune being sounded. In the form shown in Figs. 5 and 6, the rotation of the drum will cause the wires to pass successively under the 110 strikers and simultaneously receive a stroke from one striker upon one wire and a stroke

from another striker upon a second wire. The use of two striking fingers in conjunction with a proper arrangement and adjustment of the wires permits of the production of a continuous succession of harmonies, as distinguished from melodies. This, in so far as I am aware, is entirely new in toys of the general type. It will be obvious that my invention may take a variety of other forms. Hence, I do not wish to limit myself to the particular embodiments thereof which I have shown and described.

I claim:

- 15 1. A musical toy, comprising a sounding box, a series of metal rods or wires fixed to a wall of said box and representing at least a portion of a musical scale, and a pair of striking fingers adjusted with respect to each other and with respect to the wires or rods to simultaneously strike two different wires or rods and thereby produce a succession of harmonies, and means for actuating said fingers and for moving them relatively to the wires or rods whereby each finger is caused to strike the wires or rods in succession; substantially as described.
- 20 2. A musical toy, comprising a sounding box having at least one of its ends of hard wood, a series of metal wires representing at least a portion of a musical scale and secured to the hard wood end of said box, a plurality of loosely suspended striking fingers adjusted with reference to said wires and with reference to each other to simultaneously strike different wires and thereby produce a succession of harmonies, and means for actuating said fingers and for moving them relatively to the wires or rods

whereby each finger is caused to strike the wires or rods in succession; substantially as described.

3. A musical toy, comprising a series of vibratory rods or wires, an inclosing case in which said rods are secured, a movable member having a plurality of dangling striking fingers arranged to simultaneously strike different rods or wires, and a rotary shaft for actuating the said fingers and for moving them relatively to the wires or rods whereby each finger is caused to strike the wires or rods in succession; substantially as described.

4. A musical toy, comprising a series of vibratory rods driven into the inner surface of a hard wood base, an inclosing case of which the hard wood base is one of the sides, a pivoted arm provided at one end with a plurality of dangling striking fingers, and shaft means for transmitting motion from the axle to the pivoted arm, substantially as described.

5. A musical toy, comprising a sounding box, a series of vibratory rods secured at one end in a wall of said box, an oscillating member pivoted within the box above the rods, a pair of dangling striking fingers suspended from one end portion of said member, and a rotary shaft for effecting the oscillation of said member, substantially as described.

In testimony whereof, I have hereunto set my hand.

WILLIAM ALFRED GAY.
